Primary Examiner — April Rivas

(57) **CLAIM**

The ornamental design for a luggage case, as shown and described.

DESCRIPTION

FIG. 1 is a perspective view of the luggage case; FIG. 2 is a frontal view of the luggage case; FIG. 3 is a rear view of the luggage case; FIG. 4 is a right side view of the luggage case; FIG. 5 is a left side view of the luggage case; FIG. 6 is a top view of the luggage case; and, FIG. 7 is a bottom view of the luggage case. The broken lines represent portions of the structure of the luggage case that form no part of the claimed design.

1 Claim, 7 Drawing Sheets
